ENERGY ABSORBING DEVICE

Thomas M. Gluyas, Jr., Kansas City, Mo., assignor, by mesne assignments, to Pennsylvania Patents, Inc., Carson City, Nev., a corporation of Nevada

Application March 15, 1939, Serial No. 262,041

8 Claims. (Cl. 179—171.5)

This invention relates to improvements in controllable energy dissipating means for use in modulating systems of the energy absorption type. More particularly, the invention relates to energy dissipating means employing space discharge devices, and to a method of and means for eliminating the undesired effects produced by the fortuitous capacities in the space discharge devices.

In a copending application of William N. Parker, Serial No. 84,534, filed June 10, 1936, there is disclosed and claimed a modulating system of the energy absorption type which is particularly useful in the generation of a modulated high frequency carrier signal for television purposes where a wide band of frequencies must be transmitted for satisfactory picture reproduction. In that application, there are provided means for accomplishing modulation at a high level and with a considerably greater efficiency, as well as for a wider band of frequencies, than is possible with prior systems. The principal feature of the Parker system resides in shunting a high impedance source of carrier frequency energy by a controllable energy dissipating impedance which is variable in response to a modulating signal. In order that the system shall function in the most satisfactory manner, it is desirable that the modulating impedance be purely resistive, variable in magnitude in response to a modulating signal, and reduceable to zero for a reasonable value of the modulating signal on the valleys of modulation. The Parker application discloses a very satisfactory form of modulating impedance comprising a plurality of space discharge devices which serve to dissipate carrier frequency energy and thereby generate sideband components in response to the modulating signal which is impressed on their grids. The resulting impedance, which is a combination of the plate impedances of the space discharge devices, is inverted by means of a quarter wave-length transmission line or other suitable impedance-inverting means. Thus there is produced an impedance which is variable from zero to a very high value, as clearly set forth in the said Parker application.

It is observed in the Parker application that a certain amount of capacitive reactance is introduced at the modulator end of the impedance-inverter due to the inherent capacitance between the several anodes, grids and cathodes of the energy dissipating tubes. This capacitive component is inverted by the transmission line and contributes an inductive component to the impedance appearing at the other end of the line. Several means are disclosed in the said Parker

application and in a subsequent continuation-in-part thereof, Serial No. 252,204, filed January 21, 1939 whereby it is possible to overcome the effect of the tube capacitance and to produce a modulating impedance which is substantially purely resistive. One method consists in shunting the output circuits of the energy dissipating tubes by an inductance of suitable magnitude to tune out the capacitance of the tubes at the carrier frequency. Another method consists in shortening the effective electrical length of the transmission line or other impedance-inverting means coupled to the modulating tubes. In this case a capacitance may be introduced at the load end of the impedance inverter. This capacitance, in conjunction with that of the tubes at the other end of the line, operates to fill out the shortened line and to make its electrical length equal to one quarter wave length of the carrier frequency.

The present invention is directed particularly to this phase of the production of an energy dissipating device of the type disclosed in the said Parker applications. Its principal object is to provide an improved means for obtaining an inductive component in shunt with the outputs of the energy absorbing tubes in such a device. An advantage of the method of this invention is that it permits this inductive component to be introduced without the use of an actual physical inductance shunted across the outputs of the said modulating tubes.

Further features of the invention will appear from the following description and the accompanying drawing in which:

Fig. 1 is a schematic diagram of one embodiment of the invention;

Fig. 2 is an explanatory diagram which will be referred to in explaining the operation of the system of Fig. 1; and

Fig. 3 is a schematic diagram showing a modification of a portion of the circuit of Fig. 1.

Referring first to Fig. 1, there is shown a modulating system which, aside from the features of the present invention is substantially the same as that shown in the aforementioned continuation-in-part application Serial No. 252,204. For convenience of showing and for purposes of emphasis, only that portion of the circuit which constitutes the modulating impedance is shown in detail, the other portions being given conventionalized representations. Carrier frequency energy is obtained from the source S which is coupled to a junction point 2 by means of a transmission line 1 having an electrical length substantially equal to one-quarter wave length of the signal.

According to the Parker system, the impedance of the carrier source is low and is inverted to appear as a high impedance at the junction point 2. Thus there is produced at the junction point 5 2 an effective high impedance carrier frequency source. A second quarter wave line 3 connects the junction point with the load L which may be an antenna suitable for radiating the carrier frequency signal. Modulating tubes 4 have their 10 plates coupled to the junction point 2 through the line 5. The electrical length of this line is not necessarily equal to one-quarter wave length but the line may be of such a length as to form, in conjunction with the capacities appearing at its 15 two ends, an impedance inverter of effective electrical length equal to one-quarter wave length, between the plates of the tubes and the junction point. Such impedance-inverter is resonant at a frequency within a certain frequency range 20 comprising frequencies in the vicinity of the carrier frequency, and it forms an impedance substantially inversely proportional to the effective impedance of the tubes 4 for wave signals within said range. Modulating voltage is supplied between the grids and cathodes of the tubes 4 25 through the chokes 13 from the source E_m , the grids and cathodes respectively being tied together. A return lead 6 is provided between the cathodes of the modulating tubes and a center 30 tap on the inductance 7 shunted across the junction point 2, as taught by Parker, to provide a path for rectification products resulting from the modulation process. The inherent capacity introduced by the modulator tubes is represented at 35 8, and any capacity which may appear at the junction point due to the end effects of the transmission lines, as a result of the junction of several lines at a single point, or which may purposely be introduced at that point, is represented at 40 9.

According to the present invention, an inductive reactance is, in effect, made to appear in the output circuits of the space discharge devices 4 by causing a component of the carrier frequency 45 plate current, when considered as flowing out of the line 5, to lag the carrier frequency plate voltage by ninety degrees. This is accomplished by applying to the grids of the modulator tubes a voltage of carrier frequency which lags the 50 voltage in the plate circuit by the same amount. Such a voltage is obtained by changing the phase of the voltage derived from any one of a number of points in the circuit at which carrier frequency voltage appears. The change in phase may be 55 produced by a transmission line of appropriate electrical length. For example, in Fig. 1 the carrier voltage is derived from the junction point 2 and is fed back in the opposite phase to the grids of the tubes 4 by means of the transmission line 60 10 whose electrical length is substantially equal to a half-wave length or an odd number of half-wave lengths. It will be noted that blocking condensers are interposed between the transmission line 10 and the grids of tubes 4 to prevent short-circuiting of the modulating source E_m while permitting the desired feed back of the carrier voltage. The voltage on the plates of the tubes lags 65 that at the junction point by ninety degrees, and hence a component of the plate current will lag 70 the plate voltage by ninety degrees. The manner in which this obtains will be seen more clearly upon reference to Fig. 2 which is a vector diagram showing the inter-relations in phase between the various currents and voltages. The magnitude of 75 the carrier frequency voltage in the grid circuit

and that of the lagging component of plate current are exaggerated for purposes of clarity. In the diagram the following vector symbols are used:

E_j =voltage at the junction point 2
 I_j =current into the line 5 at the junction point 2.
 E_p =carrier frequency plate voltage
 E_g =carrier frequency grid voltage
 I_p =carrier frequency plate current out of the line 5 at the modulator tubes.

The magnitude of the voltage which must be fed back will depend on the magnitude of the 15 capacitance for which it is desired to compensate. For example, when the capacity shunted across the junction end of the line is negligible it may be desirable to neutralize or balance out the entire tube capacity in which case the electrical 20 length of the line 5 itself may be made equal to a quarter wave length. On the other hand, when an appreciable capacity appears at the junction point, it is preferable to have a certain amount of the tube capacity unbalanced to form in conjunction with the line 5 and the junction capacity 25 an impedance inverter whose effective electrical length is a quarter wave length of the carrier frequency. In this case the line itself may be appropriately shortened. Whatever the magnitude 30 of the capacitive component desired it may be obtained by applying to the grids of the tubes 4 a carrier frequency voltage of suitable magnitude determined, for example, by the choice of the characteristic impedance of the transmission 35 line 10.

Fig. 3 illustrates another method of feeding back carrier frequency voltage. Only that portion of the circuit is shown which is associated immediately with the modulator tubes 4. The remainder of the system may be similar to Fig. 1. The principal modification introduced in Fig. 3 is the derivation of carrier frequency voltage from the plates of the modulating tubes. In the embodiment shown this is accomplished by means of 45 high resistances 11 and capacitances 12, the resistors being connected between the plates and grids, and the condensers being connected between the grids and cathodes of the respective tubes. With the resistances sufficiently large by 50 comparison with the carrier frequency reactance of the condensers 12, the current through the series combination will be in phase with the plate voltage. The carrier voltage impressed on the grids will lag this current and the plate voltage 55 by approximately 90° in accordance with the diagram of Fig. 2.

The foregoing description of the invention has dealt solely with its application in a particular type of modulating system with reference to two 60 embodiments thereof but this should not be regarded as restricting the method to application only in the arrangements shown. For example, both of the embodiments show a pair of tubes operating in push-pull to give greater efficiency 65 and to obviate the need for a D. C. supply to their plates. It will appear that it would be feasible under certain circumstances to employ but a single tube or a plurality of tubes to which the method herein disclosed could be applied with 70 but a slight modification of the apparatus here disclosed. My invention contemplates such variations and may be regarded as applicable to modulating systems in general subject only to the restrictions imposed by the following claims.

I claim:

1. In a device for dissipating electrical wave energy having a frequency within a certain range, at a rate variable in response to a control signal; 5 energy dissipating means including a space discharge device having an anode, a cathode, and a control grid, said space discharge device having a fortuitous capacity appearing between its anode and its cathode; a source of a control signal coupled to the grid circuit of said space discharge device for controlling the energy dissipation therein; an impedance-inverter comprising a transmission line resonant at a frequency within said range, said line having one end coupled to 10 the anode circuit of said space discharge device for forming an impedance substantially inversely proportional to the impedance of said dissipative means for wave signals within said range; and further transmission line means having an input circuit and an output circuit and having an electrical length substantially equal to an odd number of half wave lengths for wave signals within said range, said last-mentioned means having its input circuit coupled to the other end of said first 15 transmission line and its output circuit coupled to the grid circuit of said space discharge device, for supplying thereto a signal whose frequency is the same as that of the energy to be dissipated and whose phase is substantially in 90° lagging relation with respect to the signal in the anode circuit of said space discharge device.
2. In a system for dissipating electrical wave energy, at a rate variable in response to a control signal; a source of wave energy to be dissipated; 35 an energy dissipating space discharge device having at least a cathode, a grid, and an anode; means for coupling said anode to said source and for forming an effective impedance inverter for inverting the impedance of said space discharge 40 device; a source of control signal coupled to the grid of said space discharge device for controlling the dissipation of energy thereby; means for deriving from the system a signal of predetermined magnitude whose frequency is substantially 45 equal to that of said wave energy and whose phase is substantially in 90° lagging relation with respect to the signal appearing at said anode; and means for applying said derived signal to the grid of said space discharge device, 50 whereby an inductive component is introduced in the impedance appearing between said anode and said cathode, said inductive component varying in such a manner with the control signal applied to said grid that said inverted impedance is substantially purely resistive for all values of control signal applied to said grid.
3. In a system for dissipating electrical wave energy having a frequency within a certain range, at a rate variable in response to a control signal; 60 energy dissipating means including a space discharge device having an anode, a cathode and a control grid, said space discharge device having fortuitous capacity appearing between its anode and its cathode; a source of a control signal coupled to the grid circuit of said space discharge device for controlling the energy dissipation therein; means coupled to the anode circuit of 65 said space discharge device forming an effective impedance inverter resonant at a frequency within said range to invert the impedance of said dissipative means for wave signals within said range; means for deriving from the system a signal whose frequency is the same as that of the energy to be dissipated and whose phase is substantially 70 in 90° lagging relation with respect to the signal in the anode circuit of said space discharge device; and means for applying said derived signal to the grid circuit of said space discharge device, whereby an inductive component is introduced in the impedance appearing between said anode and said cathode, said inductive component varying in such a manner with the control signal applied to said grid that said 75
- to the signal in the anode circuit of said space discharge device; and means for applying said derived signal to the grid circuit of said space discharge device, the magnitude of said derived signal being such as to substantially neutralize 5 the undesired capacity of said space discharge device, whereby the inverted impedance of said space discharge device is caused to be substantially purely resistive.
4. In a system for dissipating electrical wave 10 energy having a frequency within a certain range, at a rate variable in response to a control signal; energy dissipating means including a space discharge device having an anode, a cathode and a control grid, said space discharge device having 15 fortuitous capacity appearing between its anode and its cathode; a source of a control signal coupled to the grid circuit of said space discharge device for controlling the energy dissipation 20 therein; a transmission line coupled to the anode circuit of said space discharge device, said transmission line being of proper length to form in cooperation with said fortuitous tube capacity an effective impedance inverter resonant at a frequency 25 within said range to invert the impedance of said dissipative means for wave signals within said range; means for deriving from the system a signal whose frequency is the same as that of the energy to be dissipated and whose phase is 30 substantially in 90° lagging relation with respect to the signal in the anode circuit of said space discharge device; and means for applying said derived signal to the grid circuit of said space discharge device, whereby an inductive component is introduced in the impedance appearing 35 between said anode and said cathode, said inductive component varying in such a manner with the control signal applied to said grid that said inverted impedance is substantially purely resistive for all values of control signal applied to said 40 grid.
5. In a system for dissipating electrical wave energy having a frequency within a certain range, at a rate variable in response to a control signal; a source of wave signal energy to be dissipated, 45 said source having a capacitive reactive impedance component appearing across its output terminals; energy dissipating means including a space discharge device having an anode, a cathode and a control grid, said space discharge device having a fortuitous capacity appearing between its anode and its cathode; a source of a control signal coupled to the grid circuit of said space discharge device for controlling the energy dissipation 50 therein; a transmission line connected between the anode circuit of said space discharge device and said first source, said transmission line being of proper length to form in cooperation with said fortuitous tube capacity and the capacitive reactance of said first source an effective impedance inverter resonant at a frequency within 55 said range for inverting the impedance of said dissipative means for wave signals within said range; means for deriving from the system a signal whose frequency is the same as that of the energy to be dissipated and whose phase is substantially in 90° lagging relation with respect to the signal in the anode circuit of said space discharge device; and means for applying said derived signal to the grid circuit of said space 60 discharge device, whereby an inductive component is introduced in the impedance appearing between said anode and said cathode, said inductive component varying in such a manner with the control signal applied to said grid that said 65

inverted impedance is substantially purely resistive for all values of control signal applied to said grid.

6. In a device for dissipating electrical wave energy having a frequency within a certain range, at a rate variable in response to a control signal; energy dissipating means including a space discharge device having an anode, a cathode and a control grid, said space discharge device having a fortuitous capacity appearing between its anode and its cathode; a source of a control signal coupled to the grid circuit of said space discharge device for controlling the energy dissipation therein; means coupled to the anode circuit of said space discharge device for forming an effective impedance inverter resonant at a frequency within said range to invert the impedance of said dissipative means for wave signals within said range; and transmission line means having an input circuit and an output circuit and having an electrical length substantially equal to an odd number of half-wave lengths for wave signals within said range, said last-mentioned means having its input circuit coupled to said impedance inverter and its output circuit coupled to the grid circuit of said space discharge device, for supplying thereto a signal whose frequency is the same as that of the energy to be dissipated and whose phase is substantially in 90° lagging relation with respect to the signal in the anode circuit of said space discharge device, whereby an inductive component is introduced in the impedance appearing between said anode and said cathode, said inductive component varying in such a manner with the control signal applied to said grid that said inverted impedance is substantially purely resistive for all values of control signal applied to said grid.

7. In a device for dissipating electrical wave energy having a frequency within a certain range, at a rate variable in response to a control signal; energy dissipating means including a space discharge device having an anode, a cathode, and a control grid, said space discharge device having a fortuitous capacity appearing between the anode and its cathode; a source of a control signal coupled to the grid circuit of said space discharge device for controlling the energy dissipation therein; means coupled to the anode circuit of said

space discharge device for forming an effective impedance inverter resonant at a frequency within said range to invert the impedance of said dissipative means for wave signals within said range; means for deriving a signal from the anode circuit of said space discharge device of the same frequency as the energy to be dissipated; means for shifting the phase of said derived signal so as to cause it to lag the voltage in the anode circuit of said space discharge device by approximately 90°; and means for applying said derived signal to the grid circuit of said space discharge device, whereby an inductive component is introduced in the impedance appearing between said anode and said cathode, said inductive component varying in such a manner with the control signal applied to said grid that said inverted impedance is substantially purely resistive for all values of control signal applied to said grid.

8. In a device for dissipating electrical wave energy having a frequency within a certain range, at a rate variable in response to a control signal; energy dissipating means including a space discharge device having an anode, a cathode and a control grid, said space discharge device having a fortuitous capacity appearing between its anode and its cathode; a source of a control signal coupled to the grid circuit of said space discharge device for controlling the energy dissipation therein; means coupled to the anode circuit of said space discharge device for forming an effective impedance inverter resonant at a frequency within said range to invert the impedance of said dissipative means for wave signals within said range; and means including a transmission line for supplying to the grid circuit of said space discharge device a signal whose frequency is the same as that of the energy to be dissipated and whose phase is substantially in 90° lagging relation with respect to the signal in the anode circuit of said space discharge device, whereby an inductive component is introduced in the impedance appearing between said anode and said cathode, said inductive component varying in such a manner with the control signal applied to said grid that said inverted impedance is substantially purely resistive for all values of control signal applied to said grid.
